REFRIGERATOR UNIT

Original Filed June 6, 1921

FIG. 1.

FIG. 2.

INVENTOR: John R. Replogle
by Hart and Lind.
ATTORNEYS.

UNITED STATES PATENT OFFICE

JOHN B. REPROGLE, OF DETROIT, MICHIGAN, ASSIGNOR, BY MESNE ASSIGNMENTS, TO
KELVINATOR CORPORATION, OF DETROIT, MICHIGAN, A CORPORATION OF MICHIGAN

REFRIGERATOR UNIT

Original application filed June 6, 1921, Serial No. 475,344, and in Canada February 11, 1922. Divided and this application filed May 12, 1927. Serial No. 190,769.

I have filed an application in Canada Feb. 11, 1922, now Patent No. 244,990.

This invention relates to mechanical refrigeration apparatus, and more especially to such as are adapted for domestic use, the present application being a division of my copending application Serial No. 475,344 filed June 6, 1921, now Patent No. 1,823,002, patented Sept. 15, 1931.

10 In apparatus of this character, it has been common practice to place receptacles containing food or water in close proximity to the refrigerating or cooling parts so that the material contained therein will become 15 chilled or frozen thus rendering them suitable for table use.

It is an object of this invention to provide an improved and simple arrangement of these receptacles with respect to the cooling 20 parts of the apparatus, so that the function indicated will be effectively performed in a relatively short period of time.

Another object is to provide an improved means for supporting these receptacles from 25 the refrigerating or cooling parts of the apparatus.

Other objects more or less incidental to the foregoing will be obvious to those skilled in the art from an examination of the following 30 description in connection with the accompanying drawing in which:

Fig. 1 is a front elevation of a domestic refrigerator cabinet with a mechanical refrigeration apparatus installed within the 35 cooling compartment thereof, the lower portion of the cabinet being shown as broken away.

Fig. 2 is an enlarged side elevation of the vaporizer, some parts shown as broken away 40 and others in section.

In Fig. 1 is shown a household refrigerator having a cooling unit associated therewith. The refrigerator cabinet 1 may be of any suitable construction. The one shown consists of 45 a lower food compartment 2 and an upper compartment 3. The door 4 of the upper compartment 3 is shown as being open in order to show the cooling unit 5 located therein. The partition wall 6 between the two 50 compartments is provided with two ventilat-

ing openings 7 and 8 for the natural convection circulation of the air within the refrigerator. The opening 8 is arranged directly beneath the vaporizer 9 so that the cold air descending from the vaporizer 9 will flow 55 through this opening into the food compartment 2. As the temperature of this air is raised, due to its contact with the food, it will rise to the upper portions of the food compartment 2 and flow back through the opening 7 into the upper compartment 3 wherein its temperature is again lowered as it comes into contact with the vaporizer.

60 The cooling unit 5 comprises a motor-compressor-condenser unit located within the housing 10, and a vaporizer 9 supported from the housing by means of the brackets 11. The motor-compressor-condenser unit has not been shown since, so far as the present invention is concerned, any apparatus can 65 be used that is adapted to liquefy refrigerant vapor. It is also to be noted that it is not essential to this invention that the motor-compressor-condenser unit be located within the same compartment as the vaporizer. The 70 same might equally as well be placed in a different compartment of the refrigerator cabinet, or it might be located in a different room of the building. In the latter case the connecting refrigerant conduits 12 and 14 75 would, of course, be properly insulated so as to insure the efficient operation of the system.

75 The vaporizer comprises an expansion chamber or header 15 and depending refrigerant circulating conduits or coils 16, 16. The expansion chamber serves as a reservoir 80 for liquid refrigerant. The coils 16, 16 are bent to form separate loops which communicate at their ends with the interior of the said expansion chamber at spaced apart 85 points. The points of communication of the ends of each tube loop are arranged at separate levels, as shown, so as to promote the circulation of the liquid refrigerant there-through.

90 The conduit 12 conveys liquid refrigerant from the gas liquefying means located within the housing 10 to the inlet connection 17 of the expansion chamber 15. The flow of liquid refrigerant into the expansion chamber is 100

regulated by means of a float operated valve mechanism 18 which mechanism is so calibrated and arranged as to maintain the level of liquid refrigerant within the chamber at 5 a point above the uppermost ends of the coils 16, 16, thereby insuring the circulation of the liquid through the loops referred to above (see Fig. 2). As will be readily understood, the surrounding atmosphere is cooled by the 10 vaporizer by giving up its heat thereto with attendant vaporization of liquid refrigerant in the header and tubes. The vapor rises to the top of the expansion chamber from where it is conveyed back to the gas liquefying 15 means by the conduit 14.

The loops of the expansion coils 16, 16 are supported from the side wall 20 of the expansion chamber or header 15. These loops are arranged in planes parallel to each other 20 and at right angles to the side wall 20 so as to define within them a continuous space extending lengthwise of the expansion chamber. A metallic supporting member 21 is secured within the space defined by the loops 25 of the expansion coils 16, 16 and is provided with openings 22, 22 for the reception of trays 23, 23. One of the openings 22 with the tray removed is shown on the drawing. These trays are adapted to contain water or 30 other articles that are to be chilled or frozen.

It has been found that with this arrangement of the vaporizer and its expansion coils, water or other substances in the trays may be effectively frozen without the necessity of 35 employing a liquid heat conveying medium such as brine, in connection with the vaporizer or its expansion coils.

By forming the vaporizer as disclosed I have provided a very simple and effective 40 mechanical support for the trays and at the same time the fact that the liquid holding parts of the vaporizer practically surround the trays insures a highly effective cooling thereof.

45 While I have shown and described in some detail the preferred construction and preferred arrangement of the parts, it will be understood that in all respects there can be wide variations without departing from the 50 invention as defined in the appended claims.

What I claim as my invention is:

1. In refrigerating apparatus, the combination of a brineless flooded vaporizer comprising a header and a plurality of pipe loops 55 depending therefrom; means for maintaining the liquid level in the vaporizer a height sufficient to substantially fill the pipe loops and the lower part of the header; trays for food, water or the like; and means carried by 60 said pipe loops for supporting the said trays within the said loops.

2. In refrigeration apparatus, the combination of an expansion chamber; a plurality of tubes bent to form separate loops and attached at their ends to the said expansion

chamber; the said tube loops being so arranged with respect to each other as to define within them a continuous space; means for maintaining a body of liquid refrigerant in said expansion chamber and tube loops 70 at a height sufficient to substantially fill the pipe loops; a food receptacle; and supporting means for said food receptacle carried by the said tube loops and disposed within the said space defined by the loops. 75

3. In a cooling device, the combination of a header; refrigerant evaporating conduits communicating with the interior space of the said header and so arranged with respect to each other as to define within them a continuous space; means for maintaining a body of liquid refrigerant within said header and conduits at a height sufficient to substantially fill the conduits; trays for receiving articles 80 to be chilled or frozen; and a supporting member for said trays supported by the said conduits and positioned within the said space. 85

4. Refrigerating apparatus comprising the combination with a cabinet including a cooling compartment; of a vaporizer comprising an evaporating tank supported in the cabinet; a food tray supporting member; a plurality of pipes bent in the form of loops and connected at their ends to the said evaporating 90 tank, means for maintaining the liquid level in the vaporizer at a height sufficient to substantially fill the pipe loops, said loops being so arranged as to define an elongated recess 95 for supporting the said food tray supporting member. 100

5. In a refrigerating apparatus, a cooling unit adapted to be placed in the path of the medium to be cooled thereby, said cooling unit comprising heat exchange means in intimate contact with a refrigerant and with said medium to be cooled, said heat exchange means having a portion constructed and arranged to provide a freezing zone, and another portion formed to provide a cooling 110 zone in intimate thermal association with the medium flowing thereover whereby to cool the latter, the material of said second-mentioned portion lying outwardly of and spaced from the freezing zone on opposite sides 115 thereof and being so constructed and arranged as to provide, without the aid of additional means, a shield of heat-exchange material for shielding the freezing zone from the action of the circulating medium. 120

6. In a refrigerating apparatus, a cooling unit adapted to be placed in the path of the medium to be cooled thereby, said cooling unit comprising heat exchange means in intimate contact with a refrigerant and with said medium to be cooled, said heat exchange means having a portion constructed and arranged to provide a freezing zone, and another portion surrounding the freezing zone to provide a cooling zone in intimate thermal association with the cooling medium to cool 130

the latter, the material of said second-mentioned portion being so constructed and arranged as to provide without the aid of additional means, a shield of heat-exchange material for shielding the freezing zone from the action of the circulating medium.

7. In a refrigerating apparatus, a cooling unit adapted to be placed in the path of the medium to be cooled thereby, said cooling unit comprising a header and a plurality of duct means connected to the header in parallel circuit relation, said means having a portion providing a freezing zone, and another portion providing a cooling zone in intimate thermal association with the medium flowing thereover whereby to cool the latter, the material of said second-mentioned portion lying outwardly of the freezing zone in the path of the circulating medium and so constructed and arranged as to provide, without the aid of additional means, a shield of heat-exchange material for shielding the freezing zone from the action of the circulating medium.

25 8. In a refrigerating apparatus, a cooling unit adapted to be placed in the path of the medium to be cooled thereby, said cooling unit comprising a header and a plurality of ducts connected to the header in parallel circuit relation, certain of the ducts having portions co-operating with portions of other ducts to provide a freezing zone, and certain of the ducts having portions co-operating to provide a cooling zone in intimate thermal association with the medium flowing thereover whereby to cool the latter, the material of said cooling zone lying outwardly of the freezing zone in the path of the circulating medium and so constructed and arranged as to provide, without the aid of additional means, a shield of heat-exchange material for shielding the freezing zone from the action of the circulating medium.

45 9. In a refrigerating apparatus, a cooling unit including a header, opposed duct means extending downwardly from the header in spaced-apart upright planes disposed on opposite sides of said header, and means supported between said opposed duct means and in intimate metallic contact therewith for supporting an ice-freezing tray.

55 10. In a refrigerating apparatus, a cooling unit including an elongated header, opposed duct means extending downwardly from the header in spaced apart upright planes extending longitudinally of the header, and means supported between and in intimate metallic contact with said opposed duct means for carrying an ice-tray.

60 11. In a refrigerating apparatus, a series of duct loops substantially in longitudinal alignment, said duct loops having vertical leg portions lying in opposed upright spaced apart planes, and means supported between and in intimate metallic contact with said

opposed vertical leg portions for receiving an ice-tray.

12. In a refrigerating apparatus, the combination of a brineless evaporator comprising a header and plurality of pipe loops depending therefrom, said pipe loops defining a freezing chamber, means comprising a refrigerant compression and condensing mechanism for supplying refrigerant to the vaporizer, means for maintaining in the vaporizer a substantially constant body of liquid refrigerant to a depth sufficient to completely fill the pipe loops and a portion of the header, and trays for water, food or the like removably mounted within said freezing chamber.

70 13. Refrigerating apparatus comprising a cabinet having insulating walls and defining a food storage compartment within which air is circulated, means located within the cabinet comprising an evaporator for cooling the circulating air, said evaporator comprising a solid imperforate wall portion in which volatile refrigerant is contained, and dividing the cabinet into a freezing compartment within which is disposed a receptacle for containing substances to be frozen, and a food storage compartment, said wall being so constructed and arranged as to prevent the main circulating air which cools the cabinet from coming into contact with the articles disposed in the freezing compartment.

75 14. In combination, a refrigerator cabinet cooled by the circulation of air internally thereof, a refrigerant evaporating unit disposed internally of said cabinet and in direct heat exchanging relation with said circulating air, said refrigerant evaporating unit comprising a part forming a refrigerating compartment exposed externally in heat exchanging relation with said circulating air, said part having a spaced pair of unitary side portions for preventing the circulation of air therethrough between the interior and exterior of said compartment, a tray for receiving substances to be frozen disposed within said compartment, said side portions being provided with refrigerant passages wherein heat is absorbed by the refrigerant directly from the air exteriorly of said compartment, and from air and the substance to be frozen interiorly of said compartment, and means for supplying refrigerant medium to and for exhausting vaporized refrigerant from said evaporating unit.

80 110 15. Refrigerating apparatus comprising a heat insulating cabinet arranged for the circulation of air internally thereof, a refrigerant evaporating unit disposed within said cabinet and so constructed and arranged as to divide the cabinet into a freezing compartment and food storage compartment, said evaporating unit comprising a substantially planular solid metallic wall having passages formed internally thereof for the distribution

85 115 120 125 130

and evaporation of refrigerant liquid, the opposite sides of said planular solid metallic wall being so positioned as to absorb heat from the different compartments, means associated with the freezing compartment for supporting an ice tray, said means being disposed in intimate metallic contact with said wall, an ice tray on said support within the freezing compartment, and a refrigerant condensing unit operatively connected to said evaporating unit.

16. In a refrigerating apparatus, a cooling unit including a header, air cooling and ice freezing means associated with said header and comprising a substantially solid metallic wall structure operatively connected to and disposed below the header, said wall structure being provided, with refrigerant passages in communication with the header, portions of 20 said wall structure being disposed in spaced apart upright planes on opposite sides of the header and an ice freezing tray supported between said upright wall portions.

In testimony whereof I hereunto affix my
25 signature.

JOHN R. REPLOGLE.
